UNITED STATES PATENT OFFICE.

EDMUND P. KINNE, OF ALLIANCE, OHIO, ASSIGNOR TO AMERICAN STEEL FOUNDRIES,
OF CHICAGO, ILLINOIS, A CORPORATION OF NEW JERSEY.

COUPLER.

Application filed July 10, 1922. Serial No. 573,912.

To all whom it may concern:

Be it known that I, EDMUND P. KINNE, a citizen of the United States, residing at Alliance, in the county of Stark and State 5 of Ohio, have invented certain new and useful Improvements in Couplers, of which the following is a specification.

This invention relates to couplers and more particularly to means for preventing 10 the lock of a bottom lift type of coupler from creeping.

As is well known, the lock which normally holds the knuckle in its closed or normal operative position has a tendency under, operating conditions to creep toward a non-locking or inoperative position. Various means have been provided for overcoming 15 such creeping action of the lock, depending somewhat upon the type of coupler and upon 20 various contours thereof.

One object of this invention is to provide lock anti-creeping means which is simple and effective and which at the same time will not interfere with the operation of the 25 various parts of the coupler.

Another object is to provide a coupler of the bottom lift type with lock anti-creeping means which is adapted to function under 30 service conditions and meet the various requirements.

These and other objects are accomplished by means of the arrangement disclosed on the accompanying sheets of drawings, in which—

Figure 1 is a fragmentary vertical sectional view through what is known as the "D" type of bottom lift coupler, showing the lock in its locking position and toggle or trigger of the bottom lift mechanism engaged 35 the anti-creep lug;

Figure 2 is a fragmentary bottom plan view of the same coupler showing the contour of the bottom lock hole; and

Figure 3 is a sectional view similar to 45 that shown in Figure 1 with the parts in lock lift position and showing the toggle or trigger clearing the anti-creep lug.

The various novel features of the invention will be apparent from the following 50 description and drawings, and will be particularly pointed out in the appended claims.

Referring to the figures of the drawings, it will be noted that my invention is disclosed in connection with what is known as 55 the standard type "D" coupler having a

head 10 with the usual horn 11 and the spaced knuckle arms 12 between the latter of which the knuckle 13 is pivotally mounted on a pin 14. As shown in Figures 1 and 3 of the drawings, the lock proper 15 is in 60 a position for locking the knuckle 13 in closed position. In Figure 3 the lock 15 is resting upon the tail 16 of the knuckle 13, while in Figure 1 the lock 15 is elevated from the knuckle tail 16 as a result of a 65 creeping action of the lock. Were some means not provided for preventing a further creeping action of the lock 15, it ultimately would move into a position permitting the release or an opening movement of the 70 knuckle 13. This, of course, is undesirable and is to be prevented.

In this connection it will be noted that the lock 15 has a depending leg 17, the lower end of which is enlarged and is provided with an elongated diagonally arranged slot 18 in which a laterally extending projection on the bottom lift 19 is adapted to move. This enlarged head 20 at the lower end of the lock leg 17 is adapted to move vertically 75 through the lock opening 21. Mounted on the front wall of the coupler head and extending rearwardly therefrom into the lock opening 21 is a projection or anti-creep lug 22, the function of which, as a result of the 80 engagement with the bottom lift member 19, is to prevent the upward creeping movement of the lock 15. While the toggle or bottom lift member 19 heretofore has cooperated with the anti-creep lug 22 for preventing the creeping of lock 15, nevertheless 85 it has been found that under certain circumstances the lower part of the lock leg 17 has swung rearwardly to the extent that the upper trigger portion 23 of the lift member 19 is moved out from engagement with the under side of the anti-creep lug 22, thereby 90 liberating the lock 15 to creep farther toward a non-locking position. To overcome 95 this objectionable feature, I have provided means which positively prevents the locking leg 17 from moving rearwardly and thereby preventing the trigger portion 23 from accidentally moving out of engagement with the anti-creep lug 22 in a manner to permit 100 creeping action of the lock 15. In this instance such anti-creeping means takes the form of a lug 24 which extends forwardly 105 from the rear wall of the coupler head 10 into the lock leg opening 21 toward and sub-

stantially in the same vertical plane as the lug 22. Accordingly when the lock 15 is in its normal locking position, the lower rear portion of the lock leg 17 or a portion thereof, or projection 25 thereon engages the forward part of the rear anti-creep lug 24 for preventing the lower part of the lock leg 17 from swinging rearwardly and, accordingly, holding the trigger 23 of the bottom lift member 19 under and in engagement with the front anti-creep lug 22.

Referring particularly to Figure 1 of the drawings it will be noted that the lock 15 is in knuckle locking position and that the trigger 23 on the bottom lift member 19 is in engagement with the forward anti-creep lug 22 and the rear of the lock leg 17 is in engagement with the front wall of the anti-creep lug 24, thereby preventing the lock 15 from creeping into a non-locking position. It will be understood that the lateral projection at the upper end of the bottom lift member 19 is in the bottom of the slot 18 and that there is no force being applied upwardly on the bottom lift member for moving the lock into its non-locking or open position. However, with the parts arranged as shown in Figure 3, it will be noted that pressure is applied upwardly upon the lift member 19, whereupon the laterally extending projection occupies the upper end of the slot 18, in which position the trigger 23 can pass upwardly and escape the forward anti-creep lug 22 for lifting the lock 15 into a position for releasing the knuckle 13.

To make the action of the trigger and anti-creep lug 22 more positive, the trigger 23 is provided with an upper flat surface 26 which normally cooperates with the under flat surface of the forward anti-creep lug 22.

It is appreciated that there may be various modifications of the invention and it is my intention to cover all such modifications which fall within the spirit and scope of the following claims.

I claim:

1. In a coupler, the combination of a head having an opening for the passage of the leg of a lock, a knuckle pivotally connected to said head, a lock for said knuckle having a leg movable in said opening, a bottom lift member for lifting said lock from a locking position, an anti-creep lug extending into said opening adapted to be engaged by said lift member for preventing said lock from creeping into a non-locking position when said leg is in a given position, and means normally for preventing said leg taking a different position.

2. In a coupler, the combination of a head having an opening for the passage of the leg of a lock, a knuckle pivotally connected to

said head, a lock for said knuckle having a leg movable in said opening, a bottom lift member for lifting said lock from a locking position, an anti-creep lug extending into said opening adapted to be engaged by said lift member for preventing said lock from creeping into a non-locking position when said leg is in a given position, and another lug extending into said opening normally for preventing said leg taking a different position.

3. In a coupler, the combination of a head having an opening for the passage of the leg of a lock, a knuckle pivotally connected to said head, a lock for said knuckle having the leg movable in said opening, a bottom lift member for lifting said lock from a locking position, anti-creep means adapted to be engaged by said lift member for preventing said lock from creeping into a non-locking position when said leg is in a given position, and means normally for preventing said leg taking a different position.

4. In a coupler, the combination of a head having an opening, a knuckle pivotally connected to said head, a lock for locking said knuckle in an operative position and having a depending leg movable in said opening, a lock lifter slidably connected to the leg of said lock, and a plurality of lugs, one acting upon the lock lifter and the other upon the depending leg of the lock for preventing said lock from creeping into a non-locking position.

5. In a coupler, the combination of a head, a knuckle pivotally connected thereto, a lock for locking said knuckle in a given position, and a lifter slidably connected to said lock, said head having one portion for cooperating with said lifter when the latter is in one position and another portion cooperating with said lock for preventing the lock creeping into a non-locking position.

6. In a car coupler, the combination with a coupler head, a knuckle, and a vertically sliding and rearwardly swinging lock for said knuckle, of means for actuating said lock, said lock being provided with a depending leg, said coupler head being provided with an opening in its lower wall into which said leg is adapted to project, said coupler head having means cooperating with said lock actuating means for preventing said lock from accidentally assuming an unlocked position when said leg is in a given locked position, and means normally preventing said leg from assuming a substantially different position.

Signed at Alliance, Ohio, this 29th day of June, 1922.

EDMUND P. KINNE.
